UNITED STATES PATENT OFFICE

JAMES G. BLUNT, OF SCHENECTADY, NEW YORK

HUB LINER FOR RAILROAD VEHICLES

Application filed February 9, 1928. Serial No. 252,986.

This invention relates to appliances of the general class or type known as hub liners, which are interposed between the journal boxes of railroad vehicles and the wheel hubs adjoining them, for the purpose of absorbing lateral pressure in passing around curves. The type referred to is instanced in Letters Patent of the United States No. 1,551,005, granted and issued to James G. Blunt, under date of August 25, 1925, upon which the present invention is an improvement.

The object of the invention is to provide a hub liner having the operative advantages of that set forth in Patent No. 1,551,005 aforesaid, and in addition, the structural advantage of capability of application in connection with journal boxes of such form as would preclude the applicability of the hub liner of said patent.

The improvement claimed is hereinafter fully set forth.

In the accompanying drawing: Figure 1 is a vertical axial section, through a journal box and wheel hub, illustrating an application of the invention in connection therewith; Fig. 2, a side view, in elevation, of the hub liner; Fig. 3, a plan or top view thereof; and, Fig. 4, a perspective view, on an enlarged scale.

In the practice of the invention, referring descriptively to the specific embodiment thereof which is herein exemplified, a wear plate or liner is interposed between the outer end of a journal box, 1, and the hub of the adjacent wheel, 4, said liner being of sectional construction, and comprising two members or sections, 2, and 2^x. The section, 2, is in general inverted L form, as seen in side elevation, and the section, 2^x, is in general rectangular form when similarly viewed. The two sections abut, one against the other, at one end of the horizontal limb of the section, 2, and are detachably connected by a bolt, 3, passing through bolting lugs, 2^a, one on the top of the horizontal member of the section, 2, at the abutting end thereof, and the other on the top of the section, 2^x. The bolt, 3, is drawn to a tight bearing by a nut, 3^a.

The sections, 2 and 2^x, when connected to

form the complete hub liner, are supported on the top of the journal box, a bearing face, 2^y, of proper form, being provided on the lower side of the top member of the section, 2, to fit over the box.

An open topped oil recess, 2^z, is formed on the top member of the section, 2, at the end thereof further from the section, 2^x, said oil recess communicating with oiling grooves, 2°, in the faces of the sections adjoining the wheel hub. An inwardly and downwardly inclined dovetailed tongue, 2^b, is formed on each of the sections of the hub liner, said tongues being adapted to fit in similar grooves in the outer face of the journal box. The oil recess, oiling grooves, and tongues, are substantially similar to the corresponding members of the hub liner of Patent No. 1,551,005 aforesaid, and do not form part of the present invention.

It will be obvious to those familiar with the construction of railroad rolling stock, that the invention herein set forth is of substantial practical value, in the capability which it affords of application in connection with journal boxes of several types now in service, in which the space above the connecting bolt is so limited as to render it difficult, if not impossible, to obtain access to the nut of the connecting bolt, when the hub liner comprises counterpart sections abutting in the vertical axial plane of the journal box.

The invention claimed as new and desired to be secured by Letters Patent is:

1. A hub liner composed of two sections, adapted to abut one against the other, one of said sections being of substantially inverted L form, and the other of substantially rectangular form, the first specified section having a bolting lug on the abutting end of its horizontal member, and the second specified section having a corresponding bolting lug at its top; and means for connecting the sections through the bolting lugs.

2. A hub liner composed of two sections, adapted to abut one against the other, one of said sections being of substantially inverted L form and the other of substantially rectangular form, the first specified section having a bolting lug on the abutting end of

its horizontal member, and the second specified section having a corresponding bolting lug at its top, and each section having an inclined tongue, adapted to fit in a groove in a journal box; and means for connecting the sections through the bolting lugs.

3. The combination, with a journal box and a wheel and axle of a railroad vehicle, of a liner, interposed between the journal box and wheel hub, and comprising two abutting sections, one of which is of substantially inverted L form, and the other of substantially rectangular form, each of said sections having a bolting lug on its abutting side, and an inclined tongue adapted to fit in a groove in the end face of the journal box; a connecting bolt, passing through the bolting lugs; and a nut, engaging said bolt to secure the sections in place.

4. A hub liner composed of two sections, having top faces oppositely disposed, one of said sections being of substantially inverted L-shape, and the other of substantially rectangular form, the first specified section having a bolting lug on its horizontal member adjacent its said top face, and the second specified section having a bolting lug opposite said first mentioned bolting lug, said horizontal member having a lower wall for supporting the liner upon the box, oil grooves in the wheel opposed faces of the sections, a groove of one section registering with a groove of another section, an oil receiving recess on the end of the liner opposite the lugs, said oil recess being in communication with the grooves, and a bolt engaging the lugs for bolting the sections together to support the rectangular section against vertical displacement and to maintain said registry of the oil grooves.
